UNITED STATES PATENT OFFICE

1,997,334

APPARATUS FOR THE ELECTROPLATING
OF METAL OBJECTS

John Kronsbein, Smethwick, England, assignor
of one-half to Charles Frederick Neale, Bir-
mingham, England

Application January 25, 1934, Serial No. 708,202
In Great Britain February 16, 1933

1 Claim. (Cl. 204—5)

The present invention has relation to apparatus for the electro-deposition of chromium, nickel, or silver upon metal objects.

The present invention has for its object to overcome this deficiency and provide for a transitional movement of the objects in the bath which shall provide for the utmost efficiency in the operation of deposition of the chromium.

According to the present invention the objects to be treated are adapted to be moved through the electrolyte solution upon a spoked or other wheel, conveyor, or like device constructed of conductive metal, and which is essentially disposed in a vertical plane, so as to protrude above the electrolyte solution, the arrangement being such that the object to be plated enters the solution in one predetermined angle and leaves the said solution at an opposite or alternative angle, passing through all intermediate angles as may be found most advantageous in efficient plating of the article.

Conveniently the articles may be moved through, say, 180°, and this angle may be varied according to the submergence of a spoked wheel member and the angle of the protuberance or part thereon adapted to carry the objects. This particular circuitous and rotary movement of the article in a vertical plane in relation to the anode provides for a most efficient treatment thereof. The spoked wheel member may be provided with an automatic feeder and automatic remover whereby the articles may be automatically fed to the said wheel, conveyor or the like, and automatically removed therefrom when the electro-plating operation has been completed. The spoked wheel member may be driven by means of

an endless chain and sprockets or any other appropriate transmission mechanism.

The figure illustrates in plan view electroplating mechanism for the rims of cycles constructed according to the present invention.

The apparatus illustrated is particularly adapted for the application of chromium plating to rims of cycle wheels indicated by the reference letter *g*. These rims are held by clips *h* mounted upon spokes *h*. *i* are the anodes and *j* the cathode. *k* are additional anodes carried by arms *k* associated with the spokes *h*. The electrical connection between the anodes *i* and *k* is established through the main shaft *l*. The apparatus is slowly rotated as in the preceding arrangement, and a very effective application of chromium nickel or silver is possible at the rims during their submergence, then being moved through an angle of substantially 180°, this angle being of course determined by the degree of submergence.

The present apparatus is particularly designed for the mechanical plating of mass-production articles, both large and small.

What I claim as my invention and desire to secure by Letters Patent is:—

An electro-plating apparatus for the rims of cycle wheels, comprising in combination an electrolyte bath, a radially spoked member mounted upon a horizontal axis and adapted to operate in a vertical plane, said member being adapted to carry the rims at its periphery in a transverse plane, anode and cathode connections associated with the bath and additional anodes situated within the rims being carried by spokes.

JOHN KRONSBEIN.
